CLAIM

The ornamental design for a tablet holder as shown and described.

DESCRIPTION

FIG. 1 is a perspective view of a tablet holder showing my new design;

FIG. 2 is a front view of the tablet holder of FIG. 1;

FIG. 3 is a rear view of the tablet holder of FIG. 1;

FIG. 4 is a left side view of the tablet holder of FIG. 1;

FIG. 5 is a right side view of the tablet holder of FIG. 1;

FIG. 6 is a top view of the tablet holder of FIG. 1; and,

FIG. 7 is a bottom view of the tablet holder of FIG. 1;

The broken lines in FIGS. 1 through 7 depict environment only and form no part of the claimed design.

1 Claim, 7 Drawing Sheets
